UNITED STATES PATENT OFFICE.

MORRIS NAUER, OF NEW YORK, N. Y.

STATIONARY WASHBOILER.

1,275,076.

Specification of Letters Patent. Patented Aug. 6, 1918.

Application filed June 6, 1916. Serial No. 101,934.

To all whom it may concern:

Be it known that I, MORRIS NAUER, a citizen of the United States, residing at New York city, in the county of New York and State of New York, have invented certain new and useful Improvements in Stationary Washboilers; and I do hereby declare the following to be a full, clear, and exact description of the invention, such as will enable others skilled in the art to which it appertains to make and use the same.

This invention relates to a stationary wash boiler, and the primary object of the invention is to provide a wash boiler construction which includes a detergent chamber and a heating chamber positioned beneath the detergent chamber and provided for receiving a gas stove, or any other suitable heating element for heating water within the detergent chamber of the boiler.

A further object of this invention is to provide a removable asbestos lined rear wall which is spaced from the rear wall proper of the chambers of the boiler, and which is provided with an opening extending therethrough to permit of the escape of gases from the space between the auxiliary removable wall and the main wall of the boiler, which heated gases pass from the heating chamber, to an opening in the rear wall thereof into the space between the auxiliary wall and the main wall.

A still further object of this invention is to provide an attachment for permitting of the escape of steam from the detergent chamber, and also for permitting of the outlet of a surplus amount of water from the detergent chamber of the boiler, and also to provide a common outlet for the steam or overflow passage and the outlet of the detergent or cleaning chamber of the boiler.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:

Figure 1 is a perspective view of the improved boiler.

Fig. 2 is a perspective of the boiler having

the auxiliary removable back removed and showing the cover of the boiler open.

Fig. 3 is a vertical section through the boiler, taken on the line 3—3 of Fig. 1.

Fig. 4 is a horizontal section through the detergent chamber of the boiler, taken on the line 4—4 of Fig. 2.

Fig. 5 is a horizontal section through the heating chamber of the boiler taken on the line 5—5 of Fig. 3 and

Fig. 6 is a fragmentary vertical section showing the overflow and steam outlet and the main outlet of the deterging chamber.

Referring more particularly to the drawings, 1 designates the exterior casing of the stationary boiler as an entirety, which is constructed in any suitable shape, preferably rectangularly shaped having its front side 2 inclined, as clearly shown in the drawings. A partition 3 extends horizontally through the interior of the body 1 of the boiler dividing the same into an upper deterging compartment 4 and a lower heating compartment 5. A cover 6 is hingedly connected as shown at 7 to the upper rear cross piece 8 of the boiler body and it is provided for permitting access to the interior of the deterging or boiling compartment 4. A tray 9 is supported by the partition 3 and it is provided with a plurality of openings 10 to permit of the draining of the compartment 4 when desired. Suitable legs 11 are formed upon the tray 9 for supporting it above the partition 3.

A door 12 is hingedly connected to the bottom 13 of the boiler as shown at 14 permitting access to the heating compartment 5. A button 15 is provided for holding the door 12 in a closed position.

Cleats or supporting bars 16 are attached to the side of the compartment 5 for supporting a gas stove or analogous heating device as indicated in dotted lines at 17 in Fig. 5 of the drawings. The fuel supply pipe indicated by the numeral 18 in Fig. 5 passes through an opening 19 which is formed in one side of the body 1. Air holes 20 are formed in the bottom 13 for permitting of the ventilation of the heating compartment 5.

The rear end of the bottom 13 and of the upper brace bar 8 project beyond the back wall 21 of the compartment 4 and 5 and the side of the casing 1 also projects beyond the rear wall 21, as clearly shown in the draw-

ings. A removable back 22 is provided which has a piece 23 of asbestos or analogous fire proofing material mounted on its inner edge. The back 22 is held in spaced 5 relation to the back wall 21 by a frame 24 which is attached to the outer surface of the back wall 21 as clearly shown in Fig. 2 of the drawings, thereby providing a space indicated at 25 which has communication with 10 the heating compartment 5 through a slot 26 formed in the rear wall 21. The slot 26 permits the heated gases to pass from the chamber or compartment 5 into the space 25 and outwardly through an opening 27 which 15 is formed in the removable back 22. Suitable buttons 28 are carried by the edges of the sides of the body 1 for holding the removable back 22 in its proper position.

The partition 3 is provided with a drain 20 or outlet opening 28', which is normally closed by a plug 29. The outlet opening 28' communicates with the interior of a chamber 30 which is formed in the extension 31. The extension 31 projects downwardly from 25 the under surface of the partition 3 at the inner rear corner of the same and it has communication with any suitable drain or outlet waste pipe by a nipple 32 for permitting the draining of the detergent compartment of the stationary boiler.

The rear wall 21 is provided with a pair of overflow openings 33 formed therein near its upper edge, which overflow opening delivers into the interior of a member 33' 35 which is attached to the outer surface of the rear wall 21 in any suitable manner. A pipe 34 communicates with the lower end of the member 33' and with the interior of the compartment 30, for permitting of the 40 overflow of water out of the detergent chamber 4 of the boiler into the outlet chamber 30. The opening 33 will further permit steam which is formed in the boiler to pass into the member 33' and upon condensation 45 therein travel downwardly into the chamber 30.

Openings 35 are formed in the back wall 21 which openings are provided for receiving pipes for filling the compartment 4 with 50 water. The side 36 of the body 1 has its upper corner cut away as shown at 37, to provide an opening for permitting water supply pipes to extend along the rear surface of the partition 1 for communication 55 with the interior of the chamber 4 through the openings 35.

In the use of the improved stationary boiler, the clothes to be washed are placed upon the tray 9, and positioned within the 60 compartment 4, after which the required

amount of water is run into the compartment 4, through ordinary water inlet pipes through the openings 35. After the required amount of water has been run into the compartment 4, the heating element indicated by the numeral 17 is ignited, for heating the water within the boiler. The heated gases will pass from the compartment 5 through the opening 26 into the space 25 and outwardly through the opening 27. If it is so desired, the opening 27 may have communication with the chimney of a house.

Any steam which might be forced within the compartment 4 will pass outwardly 75 through the openings 33 into the member 33', and upon condensation thereof will travel downwardly through this member, the pipes 34 into the chamber 30 and outwardly through the drain 32.

The door 12 is provided for permitting ready access to the interior of the compartment 5 and for preventing the heated gases from passing outwardly out of the front side of the boiler.

From the foregoing description taken in connection with the accompanying drawings the advantages of construction and of the method of operation of the improved stationary wash boiler will be readily apparent 90 to those skilled in the art to which this invention appertains, and while in the foregoing description, the principle of the operation of this invention has been described together with various features of construction, it is to be understood that certain minor features of construction, combination and arrangement of parts may be altered to suit practical conditions provided such alterations are comprehended within the 100 scope of what is claimed.

What is claimed is:

In a stationary boiler, a casing having an upper open end, a horizontal partition secured within the casing, a perforated tray 105 supported upon the horizontal partition, said partition dividing the casing into an upper detergent chamber and a lower heating chamber, and an auxiliary rear wall secured to the casing and spaced from the rear wall thereof, each of said walls being provided with outlet openings to permit of the escape of steam and heat from the casing.

In testimony whereof I affix my signature in presence of two witnesses.

MORRIS NAUER.
